UNITED STATES PATENT OFFICE

93,614

DESIGN FOR A COMFORTABLE

Lawrence Goodstein, New York, N. Y.

Application June 30, 1934, Serial No. 52,401

Term of patent 7 years

To all whom it may concern:

Be it known that I, LAWRENCE GOODSTEIN, a citizen of the United States, residing in the city, county, and State of New York, have invented a new, original, and ornamental Design for Comfortables, of which the following is a specification; reference being had to the accompanying drawing, forming a part thereof, and in which the figure is a plan view of the comfortable according to my invention.

This design is characterized by a center part

of tufted elements in horizontal and vertical rows surrounded by a plurality of border lines about which is a border of scalloped tufts.

I claim:—

The ornamental design for a comfortable substantially as shown and described.

Signed at New York, in the county of New York and State of New York this 27th day of June 1934 A. D.

LAWRENCE GOODSTEIN.
